2 Sheets-Sheet 2

Figure 7 is a detailed circuit diagram showing a complex network of resistors, capacitors, and operational amplifiers (A, B, C, D, E, F, G) connected in a multi-stage feedback loop. The diagram is organized into several vertical columns. On the far left, there are two stages of amplifiers A and B. Amplifier A has a feedback path through resistor 17 and capacitor 24. Amplifier B has a feedback path through resistor 15 and capacitor 23. The output of amplifier B is connected to the input of amplifier C. Amplifier C has a feedback path through resistor 17 and capacitor 21. The output of amplifier C is connected to the input of amplifier D. Amplifier D has a feedback path through resistor 15 and capacitor 21. The output of amplifier D is connected to the input of amplifier E. Amplifier E has a feedback path through resistor 17 and capacitor 23. The output of amplifier E is connected to the input of amplifier F. Amplifier F has a feedback path through resistor 17 and capacitor 21. The output of amplifier F is connected to the input of amplifier G. Amplifier G has a feedback path through resistor 15 and capacitor 21. The output of amplifier G is connected to the input of amplifier D. The diagram also includes several resistors labeled 6, 17, 21, 23, 26, 27, 28, and 30, and a central vertical line with various connection points.

ELECTRIC GUN

Arthur A. Cole, Newark, N. J.

Application March 27, 1939, Serial No. 264,451

1 Claim. (Cl. 124—3)

This invention relates to improvements in ordnance devices, and more particularly to an electric gun which will include a rotatably and tiltably mounted barrel supported upon a suitable base, and provided with electro-magnetic means, whereby an iron ball or shot may be propelled through the barrel and projected from the mouth thereof at a high velocity.

An object of my invention is to provide an improved electric gun, which will include a barrel provided with spaced electro-magnets arranged along the same, in combination with a plurality of photo-electric cells and cooperating electric light bulbs arranged adjacent each of said electro-magnets, whereby the rays of light from said lights to said photo-electric cells will be intercepted by the movement of the shot along the barrel, to successively energize alternate magnets to draw the shot through the barrel and project 20 the same from the muzzle thereof.

Another object of my invention is to provide an improved electric gun consisting of a barrel suitably supported in a carriage and mounted for rotation and tilting upon a suitable support, in combination with a series of electric-magnets mounted in spaced relation along the barrel, and photo-electric cells for successively and alternately energizing said magnets, and controlled by a pair of relays for drawing a shot through the 30 barrel at increased speed and projecting the same from the muzzle thereof, at a high rate of velocity.

Other objects will appear as the description proceeds.

35 In the accompanying drawings which form a part of my application,

Figure 1 is a side elevation of my improved electric gun;

Figure 2 is a longitudinal sectional view through 40 a portion of the barrel of my improved electric gun;

Figure 3 is a vertical sectional view through the gun taken on the line 3—3 of Figure 1;

Figure 4 is a fragmentary sectional view taken 45 on the line 4—4 of Figure 1;

Figure 5 is a sectional view taken on the line 5—5 of Figure 1;

Figure 6 is a diagrammatic or schematic view 50 of the barrel with the spaced electro-magnets supported on the same, showing the wiring diagram and relays, with one set of alternate magnets energized and with the shot in the breech of the barrel in position to start its travel therethrough, and,

55 Figure 7 is a diagrammatic or schematic view

of the barrel and associated electro-magnets supported thereon, with the wiring diagram showing the other electro-magnets energized, which were not energized in Figure 6 of the drawings.

Like characters of reference are used throughout the following specification, and the accompanying drawings to designate corresponding parts.

In carrying out my invention, I provide an improved form of electric gun having a barrel 1 supported in a suitable U-shaped carriage or frame 2 which is rotatably and tiltably mounted upon the base or support 3, which may be secured to the ground in any desired manner.

The carriage or frame 2 of the gun is tiltably 15 mounted upon the bearing pin 4, and is rotatably mounted upon the bearing collar 5 at the upper end of the base or support 3.

Disposed in spaced relation along the barrel 1 of my gun, I have provided the oppositely positioned electric-magnets 6 and 7, arranged on the upper surface and lower surface of the said barrel, respectively.

The substantially U-shape guide rails 8 are supported by the lower magnets 7, and extend 25 rearwardly therefrom parallel with the barrel 1, and slightly below the same, and are secured to the lower surface of said barrel by means of the bolt 9, as clearly illustrated in Figure 4 of the drawings. Also positioned between the adjacent 30 electric-magnets 7, are a plurality of U-shape supporting brackets 10, the same being provided at the upper extremities of their side arms with the depending bearings 11, which are slidably 35 mounted upon the guide rail 8, said bearings being provided with the lock bolts 12 for holding them in the desired adjusted position. Mounted upon the left hand bearings, as viewed in Figure 3 of the drawings is an upstanding arm 13 which supports a casing or housing 14 in which is positioned the photo-electric cells 15. The surface 40 of the casing or housing 14 is curved correspondingly with the curve of the barrel 1, and contacts the same. Openings 16 and 17 are formed through the inner wall of the casing or housing 14 and through the side wall of the barrel 1, and are adapted to be aligned, for purposes hereinafter 45 set forth.

Mounted upon the bearings 11 at the right hand side of the barrel, as viewed in Figure 3 of the 50 drawings, is an upstanding arm 18 which supports the casing or housing 19 formed similarly to the casing or housing 14, its inner wall being curved to correspond to the curvature of the barrel wall, and openings 20 and 21 are formed through the 55

said inner wall and the wall of the barrel, respectively. Electric sockets 22 are mounted in the casing or housing 19, and are adapted to support the electric light bulbs 23, whereby when said 5 bulbs are illuminated, rays of light therefrom will pass through the openings 21 and 20 and across the interior of the barrel 1 and through the openings 16 and 17 to the photo-electric cells, which will be energized as long as the light rays are 10 shining upon them.

From the drawings, it will be apparent that the openings in the opposite sides of the barrel 1 comprise elongated slots, while the openings in the inner spaces of the casings or housings 14 and 19 are small round holes. From the foregoing description, it will be apparent that the supporting brackets 10 may be moved forwardly or rearwardly towards or away from the several 15 electric-magnets, whereby the timing of the effective attraction of the iron ball or shot 24 may be varied as desired.

The inner walls of the casings or housings 14 and 19 are extended considerably forward and rearward of the said housing, to effectively cover 25 the slot in the barrel 1, and recesses 25 are formed in the opposite sides of the collar portions at the upper ends of the carriage or frame 2, to receive the said elongated inner walls when they are moved rearwardly.

30 In Figures 6 and 7, I have illustrated the wiring diagram for my improved electric gun, and it will be apparent that the electric magnets A, C, E and G are connected in series with the adjacent photo-electric cells, and with the 35 winding on the relay 26, and are all simultaneously energized when the armature 27 of the said relay 26 is pulled up against the said relay. A second relay 28 is provided, its winding being 40 connected in series with the photo-electric cells and with the adjacent electro-magnets B, D and F. When the armature 27 is attracted to the relay 26, the electric bulbs adjacent the electro-magnets A, C, E and G will be illuminated, the 45 circuit being connected on one side to a generator G', through the switch 29 back through the armature 27 to the said generator. The various lamps are arranged in parallel, so that the lamp adjacent the magnets A, C, E and G will be illuminated at the same time, and when they 50 are not illuminated, the lamp adjacent the magnets B, G and F will be simultaneously illuminated.

In Figure 6 of the drawings, the circuit has 55 been illustrated to show that the magnets A, C, E and G are all energized and likewise the photo-electric cells adjacent these magnets are energized, and the light bulbs adjacent the said magnets are illuminated.

60 In Figure 7 of the drawings, I have illustrated the wiring diagram showing the relay 28 with its armature 30 attracted to it, and with the electric-magnets B, D, and F energized, and the adjacent photo-electric cells and light bulbs energized and illuminated respectively.

From the foregoing description it will be apparent that the alternate electro-magnets are connected together in series with the photo-electric cells, and are simultaneously energized, 70 at the same time the cooperating electric light bulbs are illuminated.

It will be understood that any desired means may be employed for feeding successive balls or shots 24 to the breech of the gun barrel, and 75 the operation will be the same as successive

shots passed through the barrel and from the muzzle thereof.

The mode of operation of my improved electric gun is as follows:

Assuming that the shot 24 has been placed 5 in the breech of the barrel 1, as illustrated in Figure 6 of the drawings, and the relay 26 is energized, as are the electric-magnets A, C, D and G with their adjacent photo-electric cells and the adjacent electric bulbs are illuminated. 10 The attraction caused by the magnet A being energized will draw the shot 24 along the barrel until it gets to the point where it intercepts the beam of light from the first light bulb shining on the photo-electric cell, and in thus breaking 15 the beam of light, the photo-electric cell will be caused to open the circuit to the magnet A. However, the momentum of the bullet will cause it to continue to roll or move along the barrel, at the same time the circuit is broken to the magnet A, it will be also broken to the magnets C, 20 E and G, as they are connected in series with it. Likewise at the same moment the circuit to the magnet A is broken, the relay 28 will be energized drawing the armature 30 to it, at which 25 time the magnets B, D and F will be energized as will the adjacent photo-electric cells, and the adjacent electric light bulbs will be illuminated. The ball or shot 24 will then be attracted by the magnetic force of the magnet B, and it will move 30 along the barrel until it passes through the beam of light shining from the electric light bulb adjacent the magnet C to the adjacent photo-electric cell, at which time the circuit will be instantly opened to the said magnet B and to the 35 series connected magnets D and F. Likewise, as soon as the circuit to the magnet B is opened, the relay 26 will automatically be re-energized and the magnet C, E and G, and also the magnet A will again be re-energized, and the attraction 40 of the magnet C will draw the ball or shot 24 further down the barrel, until it passes through the light beams directed from the light bulbs to the adjacent photo-electric cell, at which time the said circuit will be broken.

It will therefore be seen that the shot 24 will be drawn rapidly down the full length of the barrel, and it will gain momentum in its travel until it is projected at great force from the muzzle of the said barrel.

50 It will be further apparent that when the circuit to any of the magnets B, C, D, E, F or G is broken, the magnets adjacent thereto on each side will be energized, but the ball or shot 24 as it passes along the barrel will be attracted and 55 pulled along the barrel by the nearest magnet towards the muzzle end of the said barrel.

The effective attraction of the several magnets may be varied at will by moving the casings 14 and 19 lengthwise of the barrel so that the 60 circuit will be broken at the proper time to the various magnets, thus the speed of travel of the shot 24 may be regulated as desired to vary the force of velocity with which it leaves the barrel, with a consequence variation in the distance the 65 shot will travel.

While I have described one form of my improved electric gun and illustrated the same in the drawings, it will be understood that I do not intend to limit myself to the exact construction 70 described and illustrated, as many minor changes in detail of construction may be resorted to without departure from the spirit of the invention.

Having thus described my invention what I 75

claim as new and desire to secure by Letters Patent of the United States is:

An electric gun including a barrel having spaced aligning slots at diametrically opposed points, said slots being extended longitudinally of the barrel, a circuit including a source of electrical energy, electro-magnets disposed along the barrel in spaced relation, a closure on the barrel for each slot, each closure including a housing 5 having an opening communicating with the slot, means for adjusting each closure and housing thereon longitudinally of the barrel whereby said opening may be placed in any position along said

slots, photo-electric cells connected in series with the magnets and located in the housings at one side of the barrel, light bulbs in the housings at the opposite side of the barrel and cooperating with said cells, a projectile in said barrel, and 5 means whereby the movement of said projectile in the barrel cutting the light rays from said bulbs to the cells, automatically energizes the magnets successively to draw the projectile through the barrel and discharge the same there- 10 from.

ARTHUR A. COLE.
